UNITED STATES PATENT OFFICE.

FRANK A. POWER, OF MARLBOROUGH, MASSACHUSETTS.

DESIGN FOR AN ENGINE CHEST-PLATE AND SUPPORT.

SPECIFICATION forming part of Design No. 33,435, dated October 23, 1900.

Application filed June 6, 1900. Serial No. 19,333. Term of patent 14 years.

To all whom it may concern:

Be it known that I, FRANK A. POWER, a citizen of the United States, residing at Marlborough, in the county of Middlesex, in the State of Massachusetts, have invented and produced a new and original Design for Engine Chest-Plates and Supports, of which the following is a specification, reference being had to the accompanying drawing, forming part thereof.

The drawing represents a perspective view of my engine chest-plate and support.

1 represents an engine chest-plate of substantially-rectangular form provided with a series of perforations 2, extending around the edge of the plate, and having a lug 3 projecting from the upper edge thereof.

5 is a support or bolt of cylindrical form having jaws 6 at its lower end which engage the lug 3, a bolt 7 uniting the same by passing through the jaws and the lug. 20

8 is an abutment formed on the cylindrical bolt 5.

What I claim as new, and desire to secure by Letters Patent, is—

The design for an engine chest-plate and support, substantially as shown and described.

In testimony whereof I have affixed my signature in the presence of two witnesses.

FRANK A. POWER.

Witnesses:

OREN P. WALKER,

HARRY A. BARNARD.
